D. LAURIE.
HEEL PROTECTOR FOR HOSIERY.
APPLICATION FILED AUG. 9, 1916.

1,206,721.

Patented Nov. 28, 1916.

DONALD LAURIE, OF BICKLETON, WASHINGTON, ASSIGNOR OF ONE-HALF TO GERTRUDE B. CROW, OF BICKLETON, WASHINGTON.

HEEL-PROTECTOR FOR HOSIERY.

1,206,721.

Specification of Letters Patent. Patented Nov. 28, 1916.

Application filed August 9, 1916. Serial No. 113,932.

To all whom it may concern:

Be it known that I, DONALD LAURIE, a citizen of the United States, residing at Bickleton, in the county of Klickitat, State 5 of Washington, have invented a new and useful Heel-Protector for Hosiery; and I do hereby declare the following to be a full, clear, and exact description of the invention, such as will enable others skilled in the art 10 to which it appertains to make and use the same.

This invention relates to the art of protectors, and particularly to the kind adapted for protecting the heels of hosiery, and an object of the invention is to provide a celluloid protector, shield or guard having its sides and its rear perforated, and adapted to be interposed between the heel of the hose and the interior of the heel of the shoe, to obviate the wear of the heel of the hose, in other words to prevent the heel of the hose from rubbing on the interior surface of the heel of the shoe.

A further object of the invention is to provide a shield or protector of this kind shaped to fit the contour of the heel of the shoe and the wearer, and provided with a cork auxiliary shield or protector on the bottom of the celluloid shield, acting as an additional guard or protector and as a cushioning means.

In practical fields the details of construction may necessitate alterations falling within the scope of what is claimed.

The invention comprises further features and combination of parts as hereinafter set forth shown in the drawings and claimed.

In the drawings:—Figure 1 is a view in perspective of a portion of a stocking or sock, showing the improved shield or protector as applied to the heel thereof. Fig. 2 is a sectional view through a portion of a shoe, showing the foot of the wearer with a sock thereon, and illustrating the shield or protector adjusted in place. Fig. 3 is a detail perspective view of the protector or shield. Fig. 4 is a sectional view on line 1—4 of Fig. 3.

Referring more especially to the drawings designates the heel portion of a sock or tocking 2, and 3 denotes the heel of a shoe,

and 4 the shield, guard or protector as a whole, which may be constructed of any suitable thin, light material, such as celluloid or the like. This shield or protector 55 comprises a rear part 5 having perforations 6, the sides 7 having perforations 8, and a non-perforated bottom 9. The bottom 9, the rear 5 and the sides 7 all merge together and are so shaped as to properly conform to 60 the contour of the heel of the wearer. The perforations act to additionally lighten the shield, and at the same time to prevent the shield or protector from being too heating to the wearer. Secured adhesively, or otherwise secured to the nonperforated bottom 9 is an auxiliary shield or protector 10, which is constructed of any suitable material, preferably, cork or the like, which acts as a cushion between the dominant protector or 70 shield and the inner surface of the heel of the shoe, thereby preventing the constant pressure of the heel of the wearer, from tending to crack or otherwise injure the celluloid dominant protector. This auxiliary shield or protector blends or gradually merges forwardly and rearwardly and laterally into the outer surface of the dominant celluloid protector, and also constitutes a suitable cushion for the heel of the wearer. 80 The upper of the rear and the edges of the sides and the forward edge of the bottom all taper off, thereby insuring against any obstructions to the foot.

The invention having been set forth what 85 is claimed as new and useful is:—

1. A hosiery heel protector comprising a body constructed of celluloid having a perforated rear portion, perforated opposite sides, and a non-perforated bottom, which 90 parts merge together and are shaped to conform to the heel of the wearer and fit between the heel of the wearer and the inner surface of the heel of the shoe.

2. A hosiery heel protector comprising a 95 body constructed of celluloid having a perforated rear portion, perforated opposite sides, and a non-perforated bottom, which parts merge together and are shaped to conform to the heel of the wearer and fit between the heel of the wearer and the inner 100 surface of the heel of the shoe, and an aux-

iliary protector or shield constructed of cork secured to the non-perforated part of the body, and blending into the outer surface of the body, the upper portion of the rear and the edge portions of the sides and the forward edge portion of the bottom of the body being tapered.

In testimony whereof I have signed my name to this specification in the presence of two subscribing witnesses.

DONALD LAURIE.
